W. J. BARBER AND W. J. IRVIN.

LIQUID FUEL BURNER.

APPLICATION FILED JAN. 26, 1921. RENEWED FEB. 8, 1922.

1,430,278.

Patented Sept. 26, 1922.

UNITED STATES PATENT OFFICE.

WILLIAM J. BARBER AND WILLIS J. IRVIN, OF CLEVELAND, OHIO, ASSIGNEES, BY
MESNE ASSIGNMENTS, TO THE BARBER OIL BURNER COMPANY.

LIQUID-FUEL BURNER.

Application filed January 26, 1921, Serial No. 439,934. Renewed February 8, 1922. Serial No. 535,090.

To all whom it may concern:

Be it known that we, WILLIAM J. BARBER and WILLIS J. IRVIN, citizens of the United States, and residents of Cleveland, county 5 of Cuyahoga, State of Ohio, have jointly invented a new and useful Improvement in Liquid-Fuel Burners, of which the following is a specification, the principle of the invention being herein explained and 10 the best mode in which we have contemplated applying that principle, so as to distinguish it from other inventions.

The present improvements, relating, as indicated, to liquid fuel burners, have more 15 particular regard to burners of this type in which both the fuel and a corresponding volume of air are supplied to the burner under pressure. The object of the invention is to provide a device of this sort in 20 which a thorough intermixture of the two combustible ingredients is secured under varying conditions of pressure. A further object is to eliminate all possibility of an air bubble in the fuel line breaking the flow 25 and putting the flame out. Still another object is to render the construction extremely simple, easy to manufacture and assemble and convenient to operate.

To the accomplishment of the foregoing 30 and related ends, the invention, then consists of the means hereinafter fully described and particularly pointed out in the claims, the annexed drawing and the following description setting forth in detail 35 certain mechanism embodying the invention, such disclosed means constituting, however, but one of various mechanical forms in which the principle of the invention may be used.

40 In said annexed drawing:—

Fig. 1 is a central section through a burner embodying our present improvements; Fig. 2 is a transverse section thereof taken on the plane indicated by the line 45 2—2, Fig. 1; and Fig. 3 is a similar transverse section taken on the plane indicated by the line 3—3, Fig. 1.

In the illustrative construction illustrated 50 in said drawing, the main body 1 of the burner, which is preferably formed out of a solid casting, has a central bore 2 extending entirely therethrough. The fuel is designed to be supplied to this bore at one end, and discharged therefrom, after in-

termixture with air or like gaseous combustion supporting agent, from the other end. The fuel supply connections comprise a needle valve 3, the casing 4 of which is screw-threaded into the corresponding end of such bore 2. In order to accommodate 60 the valve to various conditions, including the supply of different kinds of liquid fuels, the inner end of the casing which is thus received in the bore 2 is preferably provided with a replaceable nozzle 5. As has 65 been previously indicated, the fuel will be supplied to the valve casing 4 under pressure, such pressure being the same as that of the air or other combustion supporting agent that is supplied to a companion valve 70 casing 6, connected with a supplemental bore or passage 7 in a lateral extension 8 from body 1. This passage 7 connects with bore 2 just beyond the nozzle 5, and the remainder of such bore, save for its discharge end, is filled with a material 9 of 75 such a character or so arranged as to present a great number of fine, irregularly disposed interstices, through which the fuel discharged from nozzle 5, along with the 80 air entering through passage 7, is obliged to pass. A needle valve 10 in valve casing 6 serves to control the supply of air, as will be 85 readily understood.

A specific form of filler for bore 2, which 90 has been found satisfactory in practice, is a cylinder made by tightly winding up a sheet of fine mesh wire gauze until it is of the proper diameter to fill such bore (see Fig. 3). A variety of equivalent devices or 95 fillers constructed of other (e. g. inert mineral) material will readily suggest themselves, it being noted that the body of the valve is not directly heated, and that the bore in question does not constitute a vaporizing chamber such as is used in most liquid fuel burners.

The discharge end of the bore 2 is enlarged to form a chamber 12 that is closed by a cap 13 save for a central orifice 14 in 100 such cap that is centrally aligned with the bore. Between the end of the latter and such orifice there is interposed a baffle plate 15, the construction of which is best shown in Fig. 2. Such baffle in other words 105 comprises a central disk 16 of a diameter less than that of chamber 12 and provided with ribs 17 spaced about its periphery, and pro-

jecting beyond its respective faces, so as to support said disk in proper position in chamber 12.

In operation, both the fuel and air line will, as previously stated, be under the same pressure. In order to start the burner a little air is turned on first, then a little of the fuel, whereupon the jet issuing through orifice 14 may be directly lighted. Then the oil is turned on full, and the air volume increased by opening valve 10 until a proper flame is secured. The pressure employed need not be high, two pounds having been found sufficient for satisfactory operation. Any kind of ordinary liquid fuel may be employed, not merely kerosene, but both heavier and lighter grades of petroleum distillates, including crude oil itself, fuel oil, etc; also alcohol and liquid hydrocarbon fuels generally. The filler in the bore 2 in the main body of the burner, under the pressure of the air supplied through passage 7, serves to effectively break up any such fuel and discharge the same into chamber 12 in finely atomized, mist-like condition, so that when the mixture finally issues through orifice 14, after passing around the baffle 15, it may, as hereinbefore stated, be directly ignited. It will be obvious that no slight interruption in the flow of fuel, such as is apt to occur if a bubble of air be included in the air line, can interrupt the operation of the burner, since there will always be a larger or smaller body of fuel in course of passage through the filler 9. In actual test our burner has been found extremely economical in the use of fuel, and capable of producing maximum temperatures.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a burner of the character described, the combination of a body having an elongated chamber filled with a material providing a multitude of fine interstices, liquid fuel and air supply lines connected with one end of such chamber and a nozzle connected with the other end thereof, said nozzle including a baffle plate provided with a plurality of spaced ribs about its circumference whereby said plate is supported transversely of such chamber-end.
2. In a burner of the character described, the combination of a body having an elongated chamber filled with a material provided with interstices forming irregular gas passageways, a fuel supply conduit connected with said passageways, an air supply

conduit communicating with said passageways above the point of entrance of said fuel supply, a baffle plate at the upper end of said chamber provided with spaced ribs about its circumference for positioning the same and permitting the passage of air in a tortuous path about its edges and a closure for the upper end of said chamber having an orifice provided centrally over said baffle plate and spaced therefrom by said rib extensions.

3. In a burner of the character described, the combination of a body having a straight elongated atomizing chamber, a material providing a multitude of fine interstices, completely filling said chamber for substantially its entire length, liquid fuel and air supply lines connected with one end of said chamber, and an apertured member associated with the other end thereof providing a restricted passageway for the discharge of the combustible mixture produced by the passage of said liquid fuel and air through said filling material.

4. In a burner of the character described, the combination of a body having an atomizing chamber, a closely rolled sheet of fine mesh wire gauze filling such chamber, liquid fuel and air supply lines connected with one end of such chamber, and an apertured cap connected with the other end thereof and providing a restricted passageway for the discharge of the combustible mixture produced by the passage of said liquid fuel and air through said filling material.

5. In a burner of the character described, the combination of a body having an atomizing chamber closely packed with a material providing a multitude of fine interstices, liquid fuel and air supply lines connected with one end of such chamber, a cap provided with a central orifice connected with the other end of such chamber, and a baffle plate provided with peripheral apertures positioned adjacent said cap transversely of the chamber end.

6. In a burner of the character described, the combination of a body having an atomizing chamber wholly filled for substantially its entire length with a material providing a multitude of fine interstices, liquid fuel and air supply lines connected with one end of such chamber, said fuel supply being provided with a fixed orifice through which the fuel must pass in a uniform volume to such elongated chamber, and a suitable nozzle connected with the other end of such chamber.

7. In a burner of the character described, the combination of a body having an elongated chamber completely filled for substantially its entire length with a material providing a multitude of fine interstices, a liquid fuel supply line connected to the base of such chamber, a replacement nozzle at the dis-

- charge end of said liquid fuel supply line adjacent said filling material, an air supply line connected to deliver compressed air through said filling material adjacent its 5 lower end, said air and gas supplies thus traversing together substantially the entire length of said material, and means at the upper end of said body for producing a spray of the inter-mixed fuel and air.
- 10 8. In a burner of the character described, the combination of a body having an elongated chamber completely filled for substantially its entire length with a material providing a multitude of fine interstices, a 15 liquid fuel supply line connected to the base of such chamber, a replacement nozzle at the discharge end of said liquid fuel supply line adjacent said filling material, an air supply line connected to deliver compressed air through said filling material adjacent its 20 lower end, said air and gas supplies thus traversing together substantially the entire length of said material, means at the upper end of said body for producing a spray of the intermixed fuel and air, and a stationary 25 baffle plate interposed between said cap and such filling material.

Signed by us, this 24th day of January, 1921.

WILLIAM J. BARBER,
WILLIS J. IRVIN.
